UNITED STATES PATENT OFFICE.

CLOISE H. BALDWIN, OF FORT WORTH, TEXAS, ASSIGNOR TO TEXAS STEEL COMPANY,
OF FORT WORTH, TEXAS, A CORPORATION OF DELAWARE.

PUMP-JACK ASSEMBLY.

Application filed February 14, 1927. Serial No. 168,076.

This invention relates to a certain new and improved pump jack assembly, and has for its object to provide, in a manner as herein-after set forth, an assembly of such class constituting a single self-contained unit thereby simplifying construction and installation and further materially reducing the cost of maintenance over the forms of pump jack assemblies now in use.

10 A further object of the invention is to provide, in a manner as hereinafter set forth, a pump jack assembly including a lubricating system which makes it possible to operate for a twenty-four hour period or longer with a 15 single application of lubricant.

Further objects of the invention are to provide, in a manner as hereinafter set forth, a pump jack assembly which is comparatively simple in its construction and arrangement, 20 strong, durable, compact, thoroughly efficient in its use, readily assembled, conveniently installed, and comparatively inexpensive to set up.

With the foregoing and other objects in view the invention consists of the novel construction, combination and arrangement of parts as hereinafter more specifically described, and illustrated in the accompanying drawings, wherein is shown an embodiment 30 of the invention, but it is to be understood that changes, variations and modifications can be resorted to which fall within the scope of the claims hereunto appended.

In the drawings wherein like reference characters denote corresponding parts throughout the several views:

Figure 1 is a side elevation of a pump jack assembly in accordance with this invention.

Figure 2 is a rear elevation partly in section, the section being upon line 2—2 Figure 1, and the structure shown in Figure 2 being upon an enlarged scale.

Figure 3 is a fragmentary view upon an enlarged scale and in vertical section of the 45 pump end of the beam.

Figure 4 is a section on line 4—4 Figure 3.

Figure 4^A is a top plan view of the bearing element for the pivoted pump or polish rod connector.

50 Figure 5 is a fragmentary view in side elevation of a modified form when a rigid supporting post is employed.

Figure 6 is a vertical sectional view of the upper portion of the modified form shown in Figure 5.

55

Figure 7 is a section on line 7—7 Figure 5.

Figure 8 is a fragmentary view in vertical section of the lower portion of the modified form shown in Figure 5.

Figure 9 is a section on line 9—9 Figure 5.

60 Referring to Figures 1 to 4^A of the drawings the pump jack assembly illustrated thereby is of the type in which a pivoted supporting structure is provided for the beam employed to operate the pump or polish rod or 65 in other words for the beam which is used to reciprocate the pump or polish rod.

The pivoted supporting structure for the beam or rather oscillatory structure for the beam comprises a pair of tubular posts 1, 2, 70 of substantial height and arranged in spaced relation, and which are connected together at their upper ends by an inverted U-shaped head member referred to generally by the reference character 3. The member 3 includes 75 a head portion 4 and a pair of depending arms 5, 6. The arm 5, as well as the arm 6 is enlarged at its lower end and the post 1, as well as the post 2 is reduced at its upper end. The arm 5, as well as the arm 6 at its lower 80 end is cut away. The upper ends of the posts 1 and 2 oppose the lower ends of the arms 5, 6 and are connected together by the holdfast devices 7. The lower ends of the arms 5 and 6 seat on the shoulders 8 provided on the posts 85 1, 2. The upper end of the post 2 is of greater thickness, as indicated at 9, and is provided with a groove 10, which opposes a groove 11 formed on the inner face of the lower end of the arm 6. The grooves 10 and 11 register to 90 provide an oil channel for conducting or rather discharging lubricant into the post 2. Formed integral with the upper end of the post 2 is an inwardly extending and upwardly inclined combined lubricant trapping and directing member 12 which leads to the inlet end of the lubricant passage or duct formed by the registering grooves 10 and 11.

95 The head part 4 of the member 3 is chambered as at 13 to form a lubricant reservoir. 100 The head part 4 is also formed with a pair of openings 14 providing supply inlets for the reservoir 13. The bottom of the reservoir 13 is formed with a pair of outlet openings 15,

with which communicate depending lubricant discharge spouts 16. Within the reservoir 13 may be positioned a body of waste 17. The arm 5 of the member 3 is formed intermediate 5 its ends with an enlarged opening 18 and the arm 6 of the member 3 intermediate the ends of said arm is formed with an enlarged opening 19. The purpose of the openings 18 and 19 will be presently referred to.

- 10 The posts 1 and 2 have secured to the lower ends thereof a rocker member, referred to generally by the reference character 20 and which consists of a cylindrical body portion 21 of substantial length. The body portion 21 in proximity to each end thereof is formed with a cylindrical extension and the said extensions are indicated at 22, 23. The extension 22 is secured within the lower end of the post 1 and the extension 23 is secured within 20 the lower end of the post 2. The body portions 21 is formed with a lengthwise extending lubricant passage 24 which has its ends terminant adjacent the ends of the body portion 21. Each end of the passage 24 terminates in a duct 25 which opens at the periphery of the body portion 21 and is positioned exteriorly of an extension 22 or 23. The extension 23 is formed with a vertically disposed channel 26 which provides means for 25 conducting the lubricant from the post 2 to the channel 24. The lubricant from the channel 24 is discharged by the ducts 25 into a bearing member 27 secured in a casing 28 mounted upon a suitable foundation or support 29. A cap member 31 is employed for retaining the rocker member 20 in the bearing 27. The lubricant which is supplied to the bearing 27 is a portion of the lubricant which is discharged from the reservoir 13 and the 30 discharge, as well as the travel, of the lubricant from the reservoir 13 will be hereinafter more specifically referred to.
- Carried by the head member 3, is a pair of oppositely disposed combined supporting and bearing elements referred to generally by the reference characters 31', 32 and as each is of the same construction, but one will be described, as the description of one applies to the other. Each combined supporting and 45 bearing element consists of a cylindrical body portion 33 formed with a socket 34 and flanged at its outer end as at 35. The socket 34 opens at the inner end of the body portion 33. The flanges 35 abut against the outer faces of the arms 5, 6. The elements 31 and 32 are fixedly secured to the arms 5, 6 by hold fast devices 36 which extend through the flanges 35 and the arms 5, 6. The holdfast devices are counter sunk in the inner faces 50 of the arms 5, 6. The lubricant discharge spouts 16 are spaced from the inner faces of the arms 5, 6 and each is positioned in alignment with a port 37 formed in the body portion 33. The port 37 opens into the socket 34, 55 The oscillatory beam which provides for

the reciprocation of the pump rod 38 is referred to generally by the reference character 39 and it is constructed from a pair of oppositely disposed channel irons 40, 41 which are arranged and maintained in spaced relation. The pump rod 38 is suspended from one end of the beam 39. A counterbalance is suspended from the other end of the beam 39 and which consists of a hanger rod 42 carrying on its lower end a weight 43. The pump 75 rod 38 as well as the hanger rod 42, are vertically adjustable relative to the ends of the beam 39 and the manner in which the rods can be adjusted will be presently referred to.

The beam 39 at a point between its transverse median and that end from which the counterbalance is suspended has secured therewith a combined suspending and pivot element 44 consisting of a body portion 45 which seats upon the channel irons 40, 41 85 and which has depending therefrom a shank 46 positioned between the channel irons 40, 41 and secured therewith by holdfast devices 47. The body portion 45 projects laterally from each of the channel irons and carries a 90 pair of oppositely disposed trunnions 48 which are mounted in the sockets 34. The ports 37, in the body portion 33 provide means for supplying lubricant to the trunnions 48. The lubricant dripping from one 95 of the trunnions 48 will be trapped by the member 12 and conducted to the post 2, and that is conducted to the interior of the post 2, by the oil conducting channel formed by the registering grooves 10 and 11. The body 100 portion 45 of the element 44 is spaced from the inner ends of the body portions 33 of the elements 31', 32. The body portion 33 of the elements 31', 32 not only provide bearings for the trunnions 48, but supports therefor. 105 The body portion 45 of the element 44 is extended as indicated at 49, see Figure 1, so that it will have sufficient purchase on the top of the beam 39.

Supported from the elements 31', 32, as well 110 as being pivotally mounted thereon, is a pair of combined supporting, shifting and retaining members referred to generally by the reference characters 50, 51 which depend from the elements 31', 32 and incline in a direction 115 towards the pump rod 38 from their upper towards their lower ends. The members 50, 51 associate with the supporting structure, or rather associate with the pivoted supporting structure and also associate with an oscillatory swing, referred to generally by the reference character 52', and which is employed for oscillating the beam 39 to provide for the reciprocation of the pump rod 38. The member 50 includes a head 52 and a tubular shank 53. The head 52 is formed with an opening 54 for mounting on the element 31' and said head 52 is also provided with a tapered port 55 arranged below the discharge spout 16 and 120 registering with a port or opening 37 and the 125

port 55 provides means for lubricating the inner face of the head 52. The lower part of the head 52 is provided with an inclined lubricant conducting channel 56 which opens into the tubular shank 53 for conducting lubricant thereto. The lower portion of the head 52 is furthermore provided with an inwardly extending and upwardly inclined combined lubricant trapping and directing element 57 which leads to the channel 56 for directing the lubricant thereto. The element 57 is arranged to trap the lubricant from the trunnion 48 which is mounted in the element 31'. The member 51 comprises a head 58 and a shank 59 and which are secured together by the holdfast devices 60. The head 58 is not provided with the channel 56, or a trapping element 57 but otherwise than that as stated it is constructed in the same manner as the head 52. That is to say it is provided with a port 55 which is arranged below the lubricant discharge spout 16. The shank 59 is tubular but no lubricant is conducted therethrough. Secured in the lower end of the shank 53, by the holdfast devices 61, is a depending plug 62, formed with a lubricant channel 63. Secured in the lower end of the shank 59 and depending therefrom, is a plug 64. The holdfast devices for securing the plug to the shank 59 are indicated at 65. The plug 62 near its lower end is formed with a diametrically disposed socket 66 which opens at the inner side of the plug, and the plug 64 at its lower end is formed with a diametrically disposed socket 67 which opens at the inner side of such plug. Extending within the sockets 66, 67 is a rock shaft 68 having reduced terminals 69 which project through the plugs and carry securing nuts 70. The shaft 68 is formed with a lengthwise disposed channel 71 having an intake 72 which registers with the channel 63 whereby the lubricant supplied to the shank 53 will be conducted to the channel 71. The outlet of the channel 71 is indicated at 73 and which opens at the periphery of the shank 68. The plugs 62 and 64 are formed with lubricant discharge ports 74 which lead from the sockets 66 and 67. The shaft 68 is mounted in a bearing 75 which is secured by the holdfast devices 76 to the swing 52' at the corner thereof. The swing 52' being of triangular contour or in the form of a bell crank. The bearing 75 is secured on the upper face of the swing 52'. The bearing 75 at each side thereof and below the port 74 is formed with laterally extending combined lubricant trapping and directing elements 77, and each of which is formed with a depending lubricant discharge spout 78 which are arranged exteriorly of the swing 52'. The elements 77 have openings 79 which register with the spouts 78. The function of the discharge spouts 78 will be presently referred to. The members 50, 51 are arranged exteriorly of the swing 52', that is to say at their lower ends, and at their upper

ends are arranged within the head member 3 of the pivoted supporting structure.

The swing 52' comprises a pair of opposed spaced longitudinally disposed channel irons 80 forming the lower arm of the swing and a pair of vertically disposed spaced bars 81 forming the upper or vertical arm of the swing. The arms of the swing are connected together by a bracing means, as indicated at 82. Secured between the channel irons which form the lower arm of the swing by the holdfast device 83, is the head 84 of a depending rocker member 85 which is mounted in a bearing 86 anchored to the casing 27. The discharge spouts 78 provides means for lubricating the rocker member 85.

Mounted on the free end of the lower arm of the swing 52', is a bearing 87, for a rocker member 88, which depends from the lower end of an actuating rod 89, for the beam 39. The upper end of the arm 89, carries a concaved cup 90 which is mounted against a globular extension 91 carried on the bottom of a lubricant container or reservoir 92, which is fixedly secured between the channel irons of the beam 39 in proximity to the pump rod 38. The lubricant from the reservoir 92 is supplied to the cup 90 by the discharge passage 93. The rod 89 pivots or fulcrums against the extension 91 when the swing 52' is shifted in a direction to provide for the upward movement of the rod 89. The securing means for the reservoir 92 is indicated as at 94.

The means for connecting the pump rod 38, as well as the hanger rod 42, to the beam 39 are of like construction, and therefore the description of one will apply to the other. The said means consists of a casting 95 formed with a reservoir 96, a vertically disposed opening 97, a pair of concavities 98, and a lubricant supply duct 99 leading from the reservoir 96 to a concavity 98. The casting 95 further includes a depending extension 100 which is arranged between the channel irons of the beam 39 and is fixedly secured therewith as at 101. Mounted on the casting 95, is a rod connecting element 102 formed with a vertically disposed opening 103 for the passage of the rod 38 or 42. The element 102 is formed with a pair of oppositely disposed trunnions 104 which are mounted in the concavities 98 and lubricated from the ducts or channels 99 due to the passage of lubricant therethrough. The rod 38 or 42 is adjustably connected to the element 102 by a pair of oppositely disposed set screws 105. The element 102 is pivotally supported in the casting 95. The elements 95 and 102 are carried with the beam 39 during the movements thereof.

Carried by the upper arm of the swing 52', at the free end of such arm is a stirrup box 106 formed with a plurality of grooves 107 for selectively receiving a stirrup 108, which is connected by the coupling 109 to the pull 130

rod 110. The stirrup box 106 is formed with a lubricant reservoir 111 and suitable channels opening into the grooves 107 for the purpose of lubricating the stirrup 108.

5 The manner of setting up the pump rod 38 and beam 39, permits the element 102 to be lifted vertically without the usual distortion, overcomes bending of the pump or polish rod, undue wear on the packing box and excessive stress on the upper sucker rod. The beam 39 is not provided with a rigid bearing, as is generally the case in jacks heretofore used, whereby the element 102 can shift, with the rod 38, in a manner to prevent bending or 10 buckling of the latter.

With respect to the modified form disclosed in Figures 5 to 9, both inclusive, it provides a pump jack assembly having a rigid supporting structure consisting of a pair of opposed standards 112, arranged in spaced relation and fixedly secured at the lower ends thereof, as at 113, to the casing 114 which is mounted or anchored upon a suitable support or base 115. Positioned between the 20 standards 112, at the upper ends thereof, as well as being fixedly secured therewith by the holdfast devices 116 are head pieces 117 each formed with an angular extension 118 to which is adjustably connected the upper 25 end of an inclined brace member 119, the latter having its lower end fixedly secured as at 120 to the casing 114. The upper end of the brace 119 is adjustably connected to the extension 118, as at 121. Two heads 117 and 30 two inclined braces 119 are employed and the heads 117 are arranged in opposed spaced relation.

Each head member 117 is provided with a pivot 122 for a vertically disposed arm 123, 40 which is formed at its lower end with an upwardly inclined extension 124, having secured therewith as at 125 a coupling member 126. Each arm 123 is formed with an inwardly extending cylindrical protuberance 45 127, formed with a socket 128, and also formed with a V-shaped port 129 which opens into the socket 128. Arranged between the arms 123 is a head member or casting 129', formed with openings 130 for the passage of 50 the protuberance 127. The casting 129' is secured to the arms 123 by the holdfast devices 131 and 132. The casting 129' at its bottom is formed with an opening 133 through which extends the beam 39.

55 Mounted on the beam 39 is a pivot member therefor comprising a body portion 134 provided with a pair of oppositely disposed trunnions 135. The body portion 134 includes a depending shank 136 which is arranged between the channel irons of the beam 39 and secured therewith by holdfast devices 137. The trunnions 135 are mounted in the sockets 128. The casting 129' at its top is formed with a lubricant reservoir 138, having a pair of outlets 139 from which depend

discharge spouts 140 arranged over the ports 129 for feeding lubricant to the socket 128.

Attached to each coupling member 126 is a downwardly extending and forwardly inclined combined bracing, retaining and shifting member 140'. The members 140' correspond to the members 50, 51 shown in Figure 2. Each member 140' is adjustably connected to a coupling member 126, as at 141. The lower ends of the members 140' are provided with angle shaped plugs 142. The plugs 142 are oppositely disposed with respect to each other and are arranged at each side of the swing 52'. A pivot 143 is provided for the plugs 142 and which also constitute means for connecting the members 140' to the swing 52'. The swing 52' carries a casting 144 provided with a lubricant reservoir 145 for supplying lubricant to the pivot 143. The pivot 143 extends through the casting 144. The rock member or pivot for the swing 52', in the form shown in Figure 5, is indicated at 146, Figure 9.

With respect to the form shown in Figure 5, it is not lubricated in the same manner as 90 the form shown in Figure 2, due to the fact that the supporting structure is of the rigid and not the rocking type.

Otherwise than that as stated the construction disclosed in the form shown in Figure 5 95 would be the same as that disclosed in the form shown by Figure 1. As before stated the lubricating arrangement is somewhat different than the form shown in Figure 5 than that with respect to the form shown in 100 Figure 1 as in Figure 5 the supporting structure is not lubricated at its lower end and the members 140' do not have means to provide for the lubrication of the pivot member 143 and the rocker 146.

The construction as disclosed in connection with each form provides a single contained unit, under such conditions simplifying construction, installation and reducing cost of maintenance, as well as providing for 110 lubrication.

It is thought the many advantages of a pump jack assembly, in accordance with this invention, can be readily understood, and although the preferred embodiment of the 115 invention is as illustrated and described, yet it is to be understood that changes in the details of construction can be had which will fall within the scope of the invention as claimed.

What I claim is:

1. A pump jack assembly comprising a counterbalanced oscillatory beam adapted to be connected at one end with a pump rod, a trunnioned supporting member connected to the beam intermediate the ends thereof, and a supporting structure for and extending above said member and including bearings for the trunnions of the latter, said supporting structure further including a lubricant 130

reservoir at its top positioned over said member and beam and means for supplying lubricant from the reservoir to the bearings for said trunnions.

- 5 2. A pump jack comprising a counterbalanced oscillatory beam adapted to be connected to a pump rod, a trunnion supporting structure for and connected to the beam, a supporting structure for said member and 10 including bearings for the trunnions of the latter, said structure further including a lubricant reservoir and means for supplying the lubricant from the reservoir for said trunnions, said supporting structure further including 15 a rocking member at its lower end, supporting means for said rocker member, and means for conducting lubricant from one of the trunnion bearings to the supporting means for the rocker member.
- 20 3. A pump jack assembly comprising a counterbalanced oscillatory beam adapted to be connected with a pump rod, a trunnioned supporting member for and connected to said beam intermediate the ends of the latter, a 25 supporting structure for and extending above said member and including bearings for the trunnions of the latter, said structure further including a lubricant reservoir at its top positioned over said member and beam and 30 means for supplying lubricant from the reservoir to the trunnion bearings, an oscillatory swing arranged adjacent to said structure, a pivoted actuating bar extended from said swing and fulcruming against and free 35 of connection with said beam, and a pair of combined shifting and retaining members pivotally connected at the lower ends thereof with the bottom of said swing and at their upper ends with said supporting structure.
- 40 4. A pump jack assembly constructed in accordance with claim 3, means for pivotally mounting the lower end of said supporting structure, and means for conducting lubricant from one of the trunnion bearings to 45 the pivotal supporting means for the lower end of said structure.

5. A pump jack assembly constructed in accordance with claim 3, means for pivotally supporting said swing, means for pivotally supporting the lower end of said supporting structure, means for conducting lubricant from one of the trunnions of said supporting member to the means for pivotally supporting the swing, and means for conducting lubricant from the other of the trunnions of the supporting member to the supporting means at the lower end of said structure.

6. In a pump jack assembly a counterbalanced, oscillatory, eccentrically mounted beam, a casting secured to one end thereof and provided at one side with a lubricant reservoir, a pair of lateral depressions centrally thereof and ports leading from the reservoir to said depressions, and a tubular pump rod connecting member provided with

trunnions seated in said depressions and further provided with means for adjustably securing the rod therewith.

7. In a pump jack assembly a counterbalanced, oscillatory, eccentrically mounted beam adapted to be connected to a pump rod, an oscillatory swing free of connection to said beam, means to provide a lubricant reservoir fixed to said beam and having a depending globular extension, a beam actuating 70 rod pivotally connected at its lower end to said swing and having its upper end provided with a semi-spherical shaped cup free of connection to and fulcruming against said extension to provide in connection with the 75 latter for universal movement of the beam with respect to said rod, said cup receiving lubricant from said reservoir.

8. A pump jack assembly comprising a base, an oscillatory swing pivotally mounted at one end thereon, a supporting structure mounted on said base adjacent said swing, a counterbalanced, oscillatory, eccentrically mounted beam adapted to be connected to a pump rod and provided with an 80 extension, a beam supporting member positioned within said structure below the top thereof, said member including a pair of trunnions mounted in the inner face of the sides of said supporting structure, a pair of combined retaining and shifting members pivotally connected with said swing at its pivoted end and with said supporting structure near its upper end, and an actuating bar pivotally connected at the lower end thereof to 85 the non-pivoted end of said swing and having its upper end fulcruming against the extension carried by the beam.

9. A pump jack assembly constructed in accordance with claim 8, means for pivotally 105 supporting the lower end of said supporting structure, means for supplying lubricant to the upper end of said actuating bar, and means at the top of said structure and positioned over said member for supplying lubricant to the trunnions of said supporting member.

10. A pump jack assembly comprising an inverted U-shaped supporting structure pivoted at its lower end, a supporting member 115 trunnioned within the inner faces of the sides of said structure below the top thereof, an oscillatory beam carried by and eccentrically mounted upon said member and extending through said structure, an oscillatory swing 120 positioned below said beam adjacent said structure, shifting connections between said structure and swing, and an actuating bar interposed between the beam and swing, said bar having its lower end pivotally connected 125 with the swing, and further having a fulcrum at its upper end coacting with the beam.

11. A pump jack assembly constructed in accordance with claim 10, said bar provided at its upper end with a semi-spherical cup, 130

said beam provided with a globular extension riding within and against the cup to provide the fulcrum for the upper end of the bar and for universal movement of the beam

5 relative to the bar.

12. A pump jack assembly constructed in accordance with claim 10, said beam formed with a depending globular extension formed with a lubricant discharge port, said bar having its upper end provided with a semi-spherical cup riding against said extension, said extension and cup forming the fulcrum for the upper end of the bar and for universal movement of the beam relative to the bar, and

15 means for supplying lubricant to said port for lubricating the extension and cup.

13. In a pump jack assembly an oscillatory beam, means for adjustably connecting a pump rod to one end thereof, means for adjustably connecting a counterbalance to the other end thereof, means carried at the ends of the beam for supplying lubricant to both of said connecting means, a trunnioned sup-

porting member for and above said beam, pivoted supporting means for said member 25 extending above and over the latter, and operating means for the beam.

14. A pump jack assembly constructed in accordance with claim 13, the said supporting means provided at its top with means 30 for lubricating the trunnions of said member.

15. In a pump jack assembly an oscillatory beam for reciprocating a pump rod, a trunnioned supporting member for said beam, a supporting structure including bearings for the trunnions of said member and further including means for supplying lubricant to such trunnions, operating means for said beam and including an oscillatory pivotally supported swing, and means for supplying lubricant from said supporting structure to the pivot for the swing.

In testimony whereof, I affix my signature hereto,

CLOISE H. BALDWIN
